(57) **ABSTRACT**
A new and distinct variety of *Phalaenopsis* plant named 'PHA682000', particularly characterized by having medium-size white flowers with yellow-green and white lips; incurving dorsal sepal curvature of longitudinal axis, medium lip curvature of lateral lobes, and weak anthocyanin coloration, and is propagated by meristem tissue culture, is disclosed.

3 Drawing Sheets

1

Genus and species: *Phalaenopsis* hybrid.
Variety denomination: 'PHA682000'.

BACKGROUND OF THE NEW PLANT

The present invention relates to a new and distinct cultivar of *Phalaenopsis* plant, botanically known as *Phalaenopsis* hybrid of the Orchidaceae family, commonly referred to as moth orchid, and hereinafter referred to by the variety name 'PHA682000'.

The new *Phalaenopsis* plant is a product of a planned breeding program conducted by the inventor in Bleiswijk, the Netherlands. The objective of this breeding program was to create a new *Phalaenopsis* plant with numerous attractive, medium-size white flowers with yellow-green and white lips suitable for potted plant production.

The new *Phalaenopsis* plant 'PHA682000' is a result of cross-pollination made by the inventor in February 2015 in Bleiswijk, the Netherlands, of the proprietary female, or seed parent, *Phalaenopsis* hybrid 'PHALFLABAL' (U.S. Plant Pat. No. 27,458) with the proprietary male, or pollen parent, *Phalaenopsis* hybrid '09-043398-01' (unpatented).

The new *Phalaenopsis* was selected by the inventor as a single plant within the progeny of the stated cross-pollination in a controlled greenhouse in Bleiswijk, the Netherlands, in September 2017. Asexual reproduction of the new *Phalaenopsis* plant by meristem tissue culture since 2018 in Bleiswijk, the Netherlands, has demonstrated that the new variety reproduces true to type with all of the characteristics, as herein described, firmly fixed and retained through successive generations.

Community Plant Variety Rights for this variety have been applied for in the European Union on Apr. 20, 2022 (Application no. 2022/1061), by Applicant who obtained the subject matter disclosed directly from the inventor. 'PHA682000' has not been made publicly available or sold anywhere in the world prior to the effective filing date of this

2

application with the exception of sales or disclosures made one year or less before the effective filing date of this claimed invention by Applicant who obtained 'PHA682000' directly from the inventor.

5 SUMMARY OF THE INVENTION

The following are the most outstanding and distinguishing characteristics of this new cultivar when grown under normal horticultural practices in Bleiswijk, the Netherlands, 10 and can be used to distinguish 'PHA682000' as a new and distinct variety of *Phalaenopsis* plant:

- 1) medium-size white flowers with yellow-green and white lips;
- 2) dorsal sepal: curvature of longitudinal axis is incurving;
- 3) lip curvature of lateral lobes is medium; and
- 4) peduncle: anthocyanin coloration is absent or weak.

DESCRIPTION OF THE PHOTOGRAPHS

20 This new *Phalaenopsis* plant is illustrated by the accompanying photographs which show the overall plant habit including blooms, buds, and foliage of the plant; the colors shown are as true as can be reasonably obtained by conventional photographic procedures. The photographs were taken in a greenhouse in Bleiswijk, the Netherlands, from 25 50-week-old plants in May 2023. Colors in the photographs may differ from the color values cited in the detailed botanical description, which accurately describe the actual colors of the new variety.

FIG. 1 shows the overall plant habit including blooms, 30 buds, and foliage of 'PHA682000'.

FIG. 2 shows a close-up of a flower of 'PHA682000'.

FIG. 3 shows an overhead, close-up view of the leaves of 'PHA682000'.

35 DESCRIPTION OF THE NEW VARIETY

The following detailed description sets forth the distinctive characteristics of 'PHA682000'. Plants of the new

Phalaenopsis have not been observed under all possible environmental conditions. The phenotype may vary somewhat with variations in environment such as temperature, light intensity, and day length, without, however, any variance in genotype. The chart used in the identification of colors described herein is The R.H.S. Colour Chart of The Royal Horticultural Society, London, England, 2015 edition, except where general color terms of ordinary significance are used. The color values were determined under 4000-6000 lux natural light in a greenhouse in Bleiswijk, the Netherlands. Observations and measurements were made in May 2023 on flowering plants which were planted in 12-centimeter (diameter) pots. After in vitro propagation, the plants were grown in nursery trays for 20-24 weeks, followed by transplantation to 12-centimeter pots and grown in a greenhouse between 27° C. to 29° C. for 30 weeks, continued by a cooling period of 8 weeks between 18° C. to 20° C. and 12 weeks in a greenhouse of 21° C. Flowering occurs after 50 weeks in 12-centimeter pots.

DETAILED BOTANICAL DESCRIPTION

Classification:

Family.—Orchidaceae.
Botanical.—*Phalaenopsis* hybrid.
Common name.—Moth orchid.
Variety name.—‘PHA682000’.

Parentage:

Female parent.—*Phalaenopsis* cultivar ‘PHALFLA-BAL’ (U.S. Plant Pat. No. 27,458).
Male parent.—*Phalaenopsis* cultivar ‘09-043398-01’ (unpatented).

Propagation:

Type.—Meristem tissue culture.

Roots:

Root description.—Greyed-green colored roots (a color in between RHS 190B and RHS 190C) with branching lateral roots having yellow-green (RHS 145A) colored root tips.

Plant:

Crop time to flowering.—Following asexual propagation (in vitro), the rooted cuttings grow for 20-24 weeks. After transplantation into 12-cm pots, the plants are finished after 48 to 50 weeks.

Growth habit of the peduncle.—Upright to slightly pendent with panicle inflorescence.

Height (from soil level to top of inflorescence).—Approximately 34.0 cm to 39.0 cm.

Width (measured from leaf tips).—About 30.0 cm to 32.0 cm.

Vigor.—Strong.

Leaves:

Mature leaves.—Quantity per plant: 9 to 10 leaves are produced before flowering. Length (fully expanded): 14.0 cm to 16.0 cm. Width: 5.5 cm to 6.5 cm. Position of the broadest part of the leaf: Toward the tip. Shape: Obovate. Base shape: Moderately elongated. Apex: Obtuse asymmetric. Leaf blade angle with the petiole (measured from the horizontal position): Between 10 degrees and 25 degrees. Leaf margin: Entire. Color: Upper surface: RHS 146A. Lower surface: RHS 146B. Texture (both upper and lower surfaces): Smooth. Thickness: 3.0 mm to 4.0 mm. Variegation: Absent. Venation: Pattern: Parallel.

Color of the midvein: Upper surface: RHS 147A. Lower surface: RHS 146A.

Peduncle:

Quantity per plant.—3.
Number of flowers per peduncle.—15 to 20.
Length.—34.0 cm to 39.0 cm.
Diameter.—5.0 mm to 6.0 mm.
Strength.—Strong.
Aspect.—Upright to slightly pendent.
Texture.—Smooth.
Color.—Green (a mix of RHS 146A and RHS 146D).
Internode length.—2.0 cm to 2.5 cm.

Inflorescence description:

Appearance.—Upright to slightly pendent, panicle inflorescence with bilaterally symmetrical flowers that open in succession beginning with the lower-most flower.

Number of inflorescences.—3.
Inflorescence size.—Height (from base to tip): 210.0 mm to 260.0 mm.

Flowering time.—First flowers can be expected 10 to 11 months after planting in a 12-cm pot.

Flower.—Height: 58.0 mm to 63.0 mm. Diameter: 65.0 mm to 70.0 mm. Depth of lip: 19.0 mm to 21.0 mm.

Flower shape.—Flat.

Flower longevity.—On the plant: 16 to 18 weeks.

Fragrance.—Absent.

Flower bud.—Average size: Medium. Length: 19.0 mm to 21.0 mm. Width: 16.0 mm to 18.0 mm. Shape: Egg shaped. Color: Light yellow-green (a color in between RHS 145C and RHS 150C).

Petals.—Arrangement: Open/free. Shape: Moderately compressed to medium. Apex: Rounded asymmetric. Margin: Entire. Length (from base to tip): 31.0 mm to 33.0 mm. Width: 41.0 mm to 43.0 mm. Position of the broadest part of the petal: Toward the base. Color (when fully opened): Upper surface: Basic color: White (RHS NN155D). Over color: Absent. Lower surface: Basic color: White (RHS NN155D). Over color: Absent. Number of spots, dots, and stripes on the petals (upper surface): None. Color of spots, dots, and stripes on the petals (upper surface): Not applicable. Density of netting of the petals (upper surface): None. Color of the netting (upper surface): Not applicable.

Dorsal sepal.—Shape: Elliptic. Apex: Obtuse symmetric. Margin: Entire. Length (from base to tip): 34.0 mm to 36.0 mm. Width: 23.0 mm to 25.0 mm. Position of the broadest part of the dorsal sepals: At the middle. Color (when fully opened): Upper surface: Basic color: White (RHS NN155D). Over color: Absent. Lower surface: Basic color: White (RHS NN155D). Over color: A touch of light yellow-green (RHS 145D) and very light purple (RHS 76B). Number of spots, dots, and stripes on the dorsal sepals (upper surface): None. Color of spots, dots, and stripes on the dorsal sepals (upper surface): Not applicable. Density of netting of the dorsal sepals (upper surface): None. Color of the netting (upper surface): Not applicable.

Lateral sepals.—Shape: Ovate. Apex: Obtuse asymmetric. Margin: Entire. Length (from base to tip): 34.0 mm to 36.0 mm. Width: 22.0 mm to 24.0 mm. Position of the broadest part of the lateral sepals: Toward the base. Color (when fully opened): Upper

surface: Basic color: White (RHS NN155D). Over color: A hint of light yellow-green (RHS 145D). Lower surface: Basic color: White (RHS NN155D). Over color: A hint of light yellow-green (RHS 145C) and a touch of light purple (RHS 76B) at the midvein toward the tip. Number of spots, dots, and stripes on the lateral sepals (upper surface): None. Color of spots, dots, and stripes on the lateral sepals (upper surface): Not applicable. Density of netting of the lateral sepals (upper surface): None. Color of the netting (upper surface): Not applicable.

Labellum (lip).—Whiskers: Present. Length of whiskers: 9.0 mm to 11.0 mm. Color of whiskers: White (RHS NN155D); light yellow-green tips (RHS 8C). Pubescence on the lip: Absent.

Lateral lobe.—Shape: Type V (as described in the International Union for the Protection of New Varieties of Plants (UPOV) Test Guidelines for *Phalaenopsis*); spatulate. Margin: Moderately undulated. Length: 17.0 mm to 19.0 mm. Width: 13.0 mm to 15.0 mm. Color: Upper surface: A touch of yellow (RHS 7A) and purplish-red stripes (RHS 71A) at the base toward one margin; greenish-yellow (RHS 153C) toward margin on one side; white (RHS NN155D) toward the other margin and the tip. Lower surface: Greenish-yellow (RHS 153D) toward margin on one side; white (RHS NN155D) toward the other margin and the tip. Number of spots and stripes on the lateral lobe: Few stripes. Color of spots and stripes on the lateral lobe: RHS 71A. Density of netting of the lateral lobe: None. Color of the netting: None.

Apical lobe.—Shape: Triangular. Margin: Entire. Length: 15.0 mm to 17.0 mm. Width: 18.0 mm to 20.0 mm. Color: Upper surface: Reddish-orange (RHS 176B) and greenish-yellow (RHS 153C) at the base; white (RHS NN155D) toward whiskers. Lower surface: Yellow (RHS 176B) margin and greenish-yellow (RHS 153D) at the base; white (RHS NN155D) toward whiskers. Number of spots and stripes on the apical lobe: None. Color of spots and stripes on the apical lobe: Not applicable. Density of netting of the apical lobe: None. Color of the netting: Not applicable. Bump and ridge: Absent.

Callus.—Average size: Medium. Height: 5.0 mm to 6.0 mm. Length: 5.0 mm to 6.0 mm. Width: 4.0 mm to 5.0 mm. Color: Greenish-yellow (RHS 5C) on sides; yellow (RHS 14A) toward tips; purplish-red dots (RHS 71A).

Reproductive organs:

Column.—Length: 7.0 mm to 8.0 mm. Diameter: 4.0 mm to 5.0 mm. Color: White (RHS NN155D).

Pollinia.—Quantity: 2. Diameter: 0.7 mm to 0.9 mm. Color: Orange-yellow (RHS 23A).

Ovary.—Length: 9.0 mm to 11.0 mm. Diameter: 2.1 mm to 2.3 mm.

Pedicel.—Length: 29.0 mm to 31.0 mm. Diameter: 2.4 mm to 2.6 mm. Color: Yellow-green (RHS 144B) at the base; light yellow-green (RHS 145B) and RHS 145D toward the flower. Texture: Smooth.

Disease, pest, and stress resistance: No specific resistance or susceptibility observed to pathogens and pests common to *Phalaenopsis* to date.

Fruit and seeds: Fruit and seed development has not been observed on plants of the new *Phalaenopsis* to date.

COMPARISON WITH PARENTAL LINES AND MOST SIMILAR VARIETIES

‘PHA682000’ differs from the female parent plant ‘PHALFLABAL’ (U.S. Plant Pat. No. 27,458) in that ‘PHA682000’ has greenish-yellow whiskers, incurving curvature of longitudinal axis, and longer leaves, whereas ‘PHALFLABAL’ has white whiskers, straight curvature of longitudinal axis, and short leaves.

‘PHA682000’ differs from the male parent plant ‘09-043398-01’ (unpatented) in that ‘PHA682000’ has more narrow flowers, shorter whiskers, and longer leaves, whereas ‘09-043398-01’ has wider flowers, longer whiskers, and shorter leaves.

‘PHA682000’ is most similar to the commercial *Phalaenopsis* plants named ‘PHALIOURG’ (U.S. Plant Pat. No. 33,099) and ‘PHALDRIDOP’ (U.S. Plant Pat. No. 28,980).

‘PHA682000’ differs from the commercial variety ‘PHALIOURG’ in that ‘PHA682000’ has more narrow flowers, moderately compressed to medium petals, and triangular apical lobes, whereas ‘PHALIOURG’ has wider flowers, medium to moderately elongated petals, and ovate apical lobes.

‘PHA682000’ differs from the commercial variety ‘PHADRIDOP’ in that ‘PHA682000’ has triangular apical lobes, shorter internodes, and wider flowers, whereas ‘PHALDRIDOP’ has trullate apical lobes, longer internodes, and more narrow flowers.

45 I claim:

1. A new and distinct variety of *Phalaenopsis* plant named ‘PHA682000’, substantially as described and illustrated herein.
